ELECTRICAL DUCT FITTING

John B. Cataldo, Birmingham, Mich., assignor to Bulldog
Electric Products Co., Detroit, Mich., a corporation
of West Virginia

Application May 28, 1956, Serial No. 41,672

Term of patent 14 years

(Cl. D26—1)

Fig. 1 is a front elevational view of the electrical duct fitting showing my novel design.

Fig. 2 is a left side elevational view of the electrical duct fitting.

Fig. 3 is a right side elevational view of the electrical duct fitting.

Fig. 4 is a top plan view of the electrical duct fitting.

Fig. 5 is a bottom plan view of the electrical duct fitting.

Fig. 6 is a perspective view of the electrical duct fitting of Figs. 1-5.

The dominant features of my new design are shown in solid lines in the drawings.

I claim:

The ornamental design for an electrical duct fitting, as shown and described.
